(57) **CLAIM**

The ornamental design for mud flap accessory, as shown and described.

DESCRIPTION

FIG. 1 is a perspective view of a mud flap accessory showing my new design;

FIG. 2 is a front view thereof;

FIG. 3 is a rear view thereof;

FIG. 4 is a left-hand view thereof;

FIG. 5 is a right-hand view thereof;

FIG. 6 is a top view thereof;

FIG. 7 is a bottom view thereof;

FIG. 8 is an environmental view with the mud flap accessory attached to a mud flap;

FIG. 9 is another front view thereof showing circled area 10; and,

FIG. 10 is exploded view of circled area 10.

The broken lines illustrate portions of the mud flap accessory that form no part of the claimed design.

1 Claim, 10 Drawing Sheets
